United States Patent Office

Des. 205,400
Patented August 2, 1966

205,400

ARTICLE STORAGE UNIT

Ross N. Bray, 32 Mayhew Drive, Lamar, Colo.

Filed Oct. 19, 1965, Ser. No. 87,595

Term of patent 14 years

(Cl. D14—6)

I claim:

The ornamental design for an article storage unit, as shown.
